(57) **CLAIM**

The ornamental design for a ladder, as shown and described.

DESCRIPTION

FIG. 1 is a perspective view of a ladder showing our new design;

FIG. 2 is a front view of the ladder and components shown in FIG. 1;

FIG. 3 is a rear view of the ladder and components shown in FIG. 1;

FIG. 4 is a left side view of the ladder and components shown in FIG. 1;

FIG. 5 is a right side view of the ladder and components shown in FIG. 1;

FIG. 6 is a top view of the ladder and components shown in FIG. 1; and,

FIG. 7 is a bottom view of the ladder shown in FIG. 1. The broken lines shown in the figures are for the purpose of illustrating portions of the ladder and form no part of the claimed design.
